CLAIM

The ornamental design for the rodent guard, as shown and described.

DESCRIPTION

FIG. 1 is a front elevational view of the rodent guard showing my new design;

FIG. 2 is a rear elevational view showing a use thereof;

FIG. 3 is a left side elevational view showing a use thereof;

FIG. 4 is a right side elevational view thereof;

FIG. 5 is a top plan view thereof; and,

FIG. 6 is a bottom plan view thereof.

The broken line showing of a portion of a door attached to the rodent guard in FIGS. 2 and 3 is for illustrative purposes only and forms no part of the claimed design.
